UNITED STATES PATENT OFFICE.

JULIUS BRENZINGER, OF MOUNT VERNON, NEW YORK, ASSIGNOR TO THE MAX AMS MACHINE COMPANY, OF BRIDGEPORT, CONNECTICUT, A CORPORATION OF NEW YORK.

FLANGING-MACHINE.

1,241,915.

Specification of Letters Patent.

Patented Oct. 2, 1917.

Application filed October 9, 1915. Serial No. 54,942.

To all whom it may concern:

Be it known that I, JULIUS BRENZINGER, a citizen of the United States, residing at Mount Vernon, in the county of Westchester 5 and State of New York, have invented certain new and useful Improvements in Flanging-Machines, of which the following is a specification.

This invention relates to flanging machines, and more particularly to machines for forming at each end of a can body the flange which is to be intercurled with the flange of the can top or head to provide the well-known double seam. The very nature of the 10 operation of flanging an endless edge of a sheet-metal body, in which what is known in an ordinary sense as solid material must be made to flow under exteriorly applied and inherently acting tensile forces of such 15 strength as to be destructive if applied too suddenly or abruptly, has undoubtedly handicapped all efforts to increase the speed and therefore the capacity of flanging machines in general, as the idea of attaining a high 20 speed of mechanical movement and that of a gradational application of forces resulting from such movement would seem to be antithetical. For this and doubtless many other 25 reasons, the development of flanging machines in the can-making art, in-so-far as 30 speed and capacity is concerned, has failed to keep pace with the development of body-forming and heading machines.

Undoubtedly a die-flanging operation may 35 be performed with reasonable certainty of success much more rapidly than a roller-flanging operation, and yet, on the other hand, it has been found practically impossible to die-flange a can body and produce a 40 flange of approved or desired configuration at one operation—that is to say, in die-flanging a second operation is generally necessary to bend down to substantially rectangular position a sufficient portion of the body of 45 the flange and sharpen the round corner between flange and body. The necessity for a second operation, as a rule, means a curtailment of capacity possibilities, and even in connection with roller-flanging it is apparent 50 that in order to effect the same result, the operation must be prolonged, so that the latter process is subject to the same objection.

One of the principal objects of the present invention is the provision of a machine

which will not only receive, flange and eject 55 a can body or can bodies with comparatively great rapidity, but one in which the flange is finished, as well as formed, without loss of time. More specifically, I have in view a machine by means of which I may avail 60 myself of the capacity possibilities of die-flanging without the usually attendant loss of time and energy heretofore required to re-shape the formed flange for the heading 65 operation. With the same ends in view, this invention contemplates a machine for simultaneously flanging both ends of the can body, thus not only saving time but simplifying construction and operation by to a large extent 70 self-supporting the work. Furthermore, I have had in mind the provision of flanging mechanism of such character that the rate of delivery of unflanged bodies thereto and ejection of flanged bodies therefrom is limited only by the duration of the 75 flanging operation. Incidental to the above, I have in view general simplicity of construction and operation, economy of power and manual attendance and dependability of character of product.

My invention will be readily understood by reference to the accompanying drawings, forming a part of this specification, in which—

Figure 1 is a side elevation of a machine 85 embodying my invention;

Fig. 2 is an end or front elevation thereof, partly in section on the line 2—2 of Fig. 1;

Fig. 3 is an enlarged partly sectional side elevation of one of the flanging dies;

Fig. 4 is a central view of an unflanged can body;

Figs. 5 and 6 are similar views of the same under action of the flanging dies and the finishing dies, respectively.

Referring now to the drawings in detail, I have shown a main supporting frame 11 which includes the legs 12 and upon which is mounted the front tilted or inclined plate or table 13. On the rear side of said frame 11 are provided brackets 14 in which is journaled the main driving shaft 15 carrying the pulley 16 which has the usual connection with a suitable source of power, said pulley being preferably connectible to and disconnectible from said shaft through the interposition of any suitable form of clutch mechanism 17 operated by means of a lever 18,

whereby the machine may be started and stopped at will.

In the upper end of the frame 11 is journaled the horizontal shaft 19, driven from the shaft 15, preferably by means of a belt 20 running over pulleys 21 and 22 on said shafts 15 and 19, respectively. Suitably journaled near the lower end of said frame 11 is journaled the shaft 23, and on the shafts 19 and 23 are mounted the sprocket wheels 24 and 25, respectively, of equal size, which carry the sprocket chain 26.

On the rear face of the tilted or inclined table 11 are mounted a plurality of journal boxes, including the boxes 27, 28 and 29, on one side of the machine, as shown in Fig. 2, and their correspondingly located counterparts on the opposite side of the machine. Referring first to these bearings on one side of the machine, as shown in Fig. 2, in each thereof is journaled a short shaft, the shaft 30 being shown in the box or bearing 27, the shaft 31 in the box or bearing 29, and the box or bearing 28 being provided with a similar shaft, which does not appear in the drawings. On the shafts 30 and 31 are mounted the equal spur-gears 32 and 33, respectively, each in mesh with a spur-pinion 34 on the shaft in the box 28.

Suitably journaled in the frame 11 is the horizontal shaft 35, driven from the shaft 15 by means of a spur-gear 36 on the latter in mesh with a spur-pinion 37 on said shaft 35. The latter also carries the bevel-gear 38 in mesh with the bevel-gear 39 on the shaft in the box 28, and in this manner, through the pinion 34 and the gears 32 and 33, the shafts 30 and 31 are rotated at the same velocity and in the same direction. The opposite counterparts of the shafts 30 and 31 and their bearings, to which I have referred, are correspondingly rotated in the same manner, at the same velocity and in the same direction.

The ends of the shafts 30 and 31 project through the plate or table 13, and in front of said plate are provided with eccentrics 40 and 41, respectively. On these eccentrics are provided studs 42 and 43, respectively, upon which is journaled a frame which includes the three die-holders 44, 45 and 46. It will be seen, therefore, that upon rotation of the shafts 30 and 31, this frame will be given bodily movement in a circular orbit, and a corresponding frame which includes the die holders 44', 45' and 46' being correspondingly mounted and similarly actuated on the other side of the machine, it will be seen that these frames simultaneously approach and recede from each other, and in approaching each other have corresponding movement at the same velocity toward the upper end of the machine.

The frame particularly described may be journaled upon the stud 42 in any common

and well-known manner, through the provision of a circular bearing and the interposition of suitable collars or gaskets, but in order to provide for unavoidable inaccuracies in the dimensions of parts in practice, I prefer to provide a yoke 47 at the lower end of the frame, the arms of which provide slide bearings for a suitable bearing block 48 which is journaled upon the stud 43, whereby the bearing at this end of the frame has a slight freedom of movement in one direction and thus provides for a certain amount of "play," so that there can be no binding or unequal wear of parts due to slight variations in sizes and inaccuracies of adjustment, yet the path of movement of the driven frame during its useful stroke being positively determined and controlled.

In each of the die-holders 45 and 46 is mounted the shank of one of the two flanging dies 49 and 50, and correspondingly located and oppositely operating dies 49' and 50' have shanks mounted in the die holders 45' and 46' in the frame on the opposite side of the machine. These dies, therefore, are counteracting, and each serves to support the work against the forces of operation of the other when can bodies to be flanged are interposed therebetween. In the die-holder 44 is mounted the shank 51 which is common to the two straightening or finishing dies 52 and 53, coöperating in a similar manner with the corresponding dies 52' and 53', the shank 51' of which is mounted in the die-holder 44' of the frame on the other side of the machine.

The sprocket chain 26 is provided with a series of carriers 54, so shaped as to engage and convey initially cylindrical can bodies through the flanging mechanisms. These can bodies 55 may be fed to this conveyer through the medium of a chute 56, so inclined as to deliver said can bodies successively to the conveyers 54 by gravity, each body being engaged and retained in a substantially horizontal position by one of said carriers, the latter being equidistantly spaced apart, and while traveling over the flat front face of the plate or table 13 so spacing said bodies apart as to properly position the same for engagement by the flanging dies. In Fig. 2, the two can bodies 55' are shown while the same are being subjected to the actions of the dies 49 and 50 and their opposite counterparts 49' and 50', while the can bodies 55'' are shown in position where the straightening or finishing operations are being performed by the dies 52 and 53 and their opposite counterparts 52' and 53'. The movement of the chain 26 is continuous and uniform, and the can bodies are consequently moving at a uniform velocity with said chain throughout the flanging operations. Therefore, the velocity of the revolving die-carrying frames is 130

made, through their actuating connections with the driving shaft 15, the same as the velocity of the chain 26, wherefore both the flanging and the straightening dies move 5 with said can bodies during the flange forming and flange completing operations, and there is no interruption of movement of any part of the machine.

As hereinbefore set forth, the flanging dies 49, 50, 49' and 50' are identical in construction and are similarly mounted and operated. Therefore, a detailed description of one will suffice for all thereof. As shown in Fig. 3, the carrier 45 is provided with a 10 cylindrical bore within which is seated the shank 57 of the die 49. Near the outer end of this bore is provided the adjusting plug 58, which is rigidly held in the desired position in said bore by means of the shank 20 59 of the clamping bolt 60. Threaded through the plug 58 is the adjusting screw 61, against the end of which the end of the die-shank 57 abuts. By means of this screw 61, therefore, the relative location of the die 25 49 may be determined, and said die rigidly retained in this adjusted position by means of the shank 62 of a clamping bolt 63 engaging the die-shank 57.

The operating face of the die 49 preferably 30 comprises the tapering face 63, adapted to first engage the end edge of the can body 55' and in operating properly position said body to a higher degree of exactness than would be possible with the carriers 54 35 alone. The tapering face 63 terminates in a cylindrical portion which is of substantially the same diameter as the internal diameter of the body 55', and this cylindrical portion terminates in an outwardly curved portion 40 which directs the end edge of the body 55' outwardly to practically form the desired flange, a ring 64 being preferably provided to prevent over-flanging and to insure a substantially circular flange end.

In thus positively determining and controlling the flow of the metal in the formation of this flange, it will be apparent that the inherent resiliency of the metal operated upon will tend to bind a can body upon 45 the die and interfere with ready dislodgment of said body from the dies when the latter are moved away from each other. To overcome the friction due to these binding forces, I have shown the die-head divided 50 55 into two parts, a rigid part 49, and a part 65 pivoted to said rigid part near the edge thereof and having a limited pivotal movement with respect thereto. Suitable sockets are provided in the contiguous faces of 60 these parts for the interposition of a compression spring 66 therebetween, said spring yielding readily to the forces of the flanging operation, but having sufficient power to overcome the friction of the binding forces 65 to which I have referred, thus forcing one

edge of the can body 55' out of its seat in the die, as clearly shown in Fig. 3, following which the die may be readily removed without movement of the can body therewith.

The finishing dies 52 and 53 and their opposite counterparts 52' and 53' consist in flat disks which have the effect of merely flattening the rounded flange which has been formed by the flanging dies, and sharpening the rounded corner, as shown in Fig. 6, thus giving the completed flange a configuration best adapted to receive the flanged top and be intercurled therewith by the usual double-seaming operation.

After this finishing operation, the flanged can bodies continue their upward movement progressively with the carriers 54, to be finally discharged upon a suitable chute 67, which directs them under action of gravity to a heading machine or to any other ultimate point of delivery.

From the foregoing it will be seen that I have provided a flanging machine which may be practically and successively operated at great speed; which will simultaneously 90 flange both ends of a can body in transit without interruption of advancing movement; which, while employing die-flanging mechanism that requires two operations for completion of the flange, so performs these 95 operations that there is no loss of time, as the second operation is completed by the finishing dies while the first operation is being completed by the flanging dies; which is comparatively simple in construction, due 100 to making the work self-supporting by simultaneously flanging both ends of the can body, and for many other reasons; which is simple and dependable in operation, comparatively light in weight, and 105 which requires a minimum of manual attendance.

Many modifications of minor details of my improved flanging machine will doubtless readily suggest themselves to those 110 skilled in the art to which it appertains, and I therefore do not desire to limit my invention to the specific construction herein shown and described.

I claim as new and desire to secure by Letters Patent:

1. In a flanging machine, the combination, with means for advancing can bodies in continuous procession through the machine, of counteracting flanging dies intermittently 120 operable to simultaneously perform the several steps of a complete flanging operation upon both ends of a plurality of can bodies in transit without interruption of advancing movement.

2. In a flanging machine, the combination, with means for rectilinearly advancing can bodies in continuous procession through the machine, of counteracting flanging dies intermittently operable to simultaneously per- 130

form the several steps of a complete flanging operation upon both ends of a plurality of can bodies in transit without interruption of advancing movement.

5. 3. In a flanging machine, the combination, with means for advancing can bodies in continuous procession through the machine, of flange-forming dies and flange-finishing dies intermittently operable to form a flange at each end of an advancing can body and simultaneously finish the formed flanges on the preceding can body without interruption of advancing movement.

10. 4. In a flanging machine, the combination, with means for advancing can bodies in continuous procession through the machine, of flange-forming dies and flange-finishing dies intermittently operable to form flanges at each end of a plurality of advancing can bodies and simultaneously finish the formed flanges on a plurality of preceding can bodies without interruption of advancing movement.

15. 5. In a flanging machine, the combination, with means for advancing can bodies in continuous procession through the machine, of flange-forming dies and flange-finishing dies intermittently operable to form a flange at each end of an advancing can body and simultaneously finish the formed flanges on the preceding can body without interruption of advancing movement, said forming and finishing dies having common supporting and actuating means.

20. 6. In a flanging machine, the combination, with means for advancing can bodies in continuous procession through the machine, of flange-forming dies and flange-finishing dies intermittently operable to form a flange at each end of a plurality of advancing can bodies and simultaneously finish the formed flanges on a plurality of preceding can bodies without interruption of advancing movement, said forming and finishing dies having common supporting and actuating means.

25. 7. In a flanging machine, the combination, with means for advancing can bodies in continuous procession through the machine, of movable carriers having counteracting flanging dies mounted thereon, and means for actuating said carrier to simultaneously perform the several steps of a complete flanging operation upon both ends of a plurality of can bodies in transit without interruption of advancing movement.

30. 8. In a flanging machine, the combination, with means for rectilinearly advancing can bodies in continuous procession through the machine, of movable carriers having counteracting flanging dies mounted thereon, and means for actuating said carrier to simultaneously perform the several steps of a complete flanging operation upon both ends of a plurality of can bodies in transit

without interruption of advancing movement.

9. In a flanging machine, the combination, with means for advancing can bodies in continuous procession through the machine, of movable carriers having flange-forming dies and flange-finishing dies mounted thereon, and means for actuating said carriers to intermittently operate said dies to form a flange at each end of an advancing can body and simultaneously finish the formed flanges on the preceding can body without interruption of advancing movement. 70 75

10. In a flanging machine, the combination, with means for advancing can bodies in continuous procession through the machine, of movable carriers having flange-forming dies and flange-finishing dies mounted thereon, and means for actuating said carriers to intermittently operate said dies to form flanges at each end of a plurality of advancing can bodies and simultaneously finish the formed flanges on a plurality of preceding can bodies without interruption of advancing movement. 96

11. In a flanging machine, the combination, with an endless conveyer provided with means for receiving, progressively advancing and finally discharging can bodies, and means for operating said conveyer continuously, of counteracting flanging dies intermittently operable to simultaneously perform the several steps of a complete flanging operation upon both ends of a plurality of can bodies in transit without interruption of advancing movement. 95 100

12. In a flanging machine, the combination, with an endless conveyer provided with means for receiving, progressively advancing in a rectilinear path and finally discharging can bodies, and means for operating said conveyer continuously, of counter-acting flanging dies intermittently operable to simultaneously flange both ends of a plurality of can bodies in transit without interruption of advancing movement. 105 110

13. In a flanging machine, the combination, with an endless conveyer provided with means for receiving, progressively advancing and finally discharging can bodies, and means for operating said conveyer continuously, of flange-forming dies and flange-finishing dies intermittently operable to form a flange at each end of an advancing can body and simultaneously finish the formed flanges on the preceding can body without interruption of advancing movement. 115 120

14. In a flanging machine, the combination, with an endless conveyer provided with means for receiving, progressively advancing and finally discharging can bodies, and means for operating said conveyer continuously, of flange-forming dies and flange-finishing dies intermittently operable to 125 130

form flanges at each end of a plurality of advancing can bodies and simultaneously finish the formed flanges on a plurality of preceding can bodies without interruption of advancing movement.

15. In a flanging machine, the combination, with an endless conveyer provided with means for receiving, progressively advancing and finally discharging can bodies, and means for operating said conveyer continuously, of flange-forming dies and flange-finishing dies intermittently operable to form a flange at each end of an advancing can body and simultaneously finish the formed flanges on the preceding can body without interruption of advancing movement, said forming and finishing dies having common supporting and actuating means.

16. In a flanging machine, the combination with an endless conveyer provided with means for receiving, progressively advancing and finally discharging can bodies, and means for operating said conveyer continuously, of flange-forming dies and flange-finishing dies intermittently operable to form flanges at each end of a plurality of advancing can bodies and simultaneously finish the formed flanges on a plurality of preceding can bodies without interruption of advancing movement, said forming and finishing dies having common supporting and actuating means.

17. In a flanging machine, the combination, with an endless conveyer provided with means for receiving, progressively advancing in a rectilinear path and finally discharging can bodies, and means for operating said conveyer continuously, of movable carriers having counteracting flanging dies mounted thereon, and means for actuating said carriers in endless paths in the same plane to simultaneously flange both ends of a can body in transit without interruption of advancing movement.

45. 18. In a flanging machine, the combination, with an endless conveyer provided with means for receiving, progressively advancing in a rectilinear path and finally discharging can bodies, and means for operating said conveyer continuously, of movable carriers having counteracting flanging dies mounted thereon, and means for actuating said carriers in endless paths in the same plane to simultaneously flange both ends of a plurality of can bodies in transit without interruption of advancing movement.

19. In a flanging machine, the combination, with an endless conveyer provided with means for receiving, progressively advancing and finally discharging can bodies, and means for operating said conveyer continuously, of movable carriers having flange-forming dies and flange-finishing dies mounted thereon, and means for actuating

ing said carriers in endless paths in the same plane to intermittently operate said dies to form a flange at each end of an advancing can body and simultaneously finish the formed flanges on the preceding can body.

20. In a flanging machine, the combination, with an endless conveyer provided with means for receiving, progressively advancing in a rectilinear path and finally discharging can bodies, and means for operating said conveyer continuously, of movable carriers having flange-forming dies and flange-finishing dies mounted thereon, and means for actuating said carriers in endless paths in the same plane to intermittently operate said dies to form a flange at each end of an advancing can body and simultaneously finish the formed flanges of the preceding can body.

21. In a flanging machine, the combination, with an endless conveyer provided with means for receiving, progressively advancing and finally discharging can bodies, and means for operating said conveyer continuously, of movable carriers having flange-forming dies and flange-finishing dies mounted thereon, and means for actuating said carriers in endless paths in the same plane to intermittently operate said dies to form a flange at each end of a plurality of advancing can bodies and simultaneously finish the formed flanges on a plurality of preceding can bodies.

22. In a flanging machine, the combination, with an endless conveyer provided with means for receiving, progressively advancing in a rectilinear path and finally discharging can bodies, and means for operating said conveyer continuously, of movable carriers having flange-forming dies and flange-finishing dies mounted thereon, and means for actuating said carriers in endless paths in the same plane to intermittently operate said dies to form a flange at each end of a plurality of advancing can bodies and simultaneously finish the formed flanges on a plurality of preceding can bodies.

23. In a machine of the character described, the combination, with means for advancing the work continuously in a rectilinear path, of oppositely located tool carriers, a first-action tool and a second-action tool on each carrier, and means for actuating said carriers to bring said tools simultaneously into work-engaging positions in curvilinear paths in the direction of the advancing work.

24. In a machine of the character described, the combination, with means for continuously advancing the work, of oppositely located tool carriers, a first-action tool and a second-action tool on each carrier, and means for actuating said carriers in endless paths in the same plane to bring said tools

simultaneously into work-engaging positions in curvilinear paths in the direction of the advancing work.

25. In a machine of the character described, the combination, with means for continuously advancing the work, in a rectilinear path, of oppositely located tool carriers, a first-action tool and a second-action tool on each carrier, and means for actuating said carriers in endless paths in the same plane to bring said tools simultaneously into work-engaging positions in the direction of the advancing work and without interruption of advancing movement.

15 26. In a machine of the character described, the combination, with means for advancing the work continuously, of oppositely located tool carriers, a plurality of first-action tools and a plurality of second-action tools on each carrier, and means for actuating said carriers to bring said tools simultaneously into work-engaging positions in curvilinear paths in the direction of the advancing work.

25 27. In a machine of the character described, the combination, with means for continuously advancing the work, of oppositely located tool carriers, a plurality of first-action tools and a plurality of second-action tools on each carrier, and means for actuating said carriers in endless paths in the same plane to bring said tools simultaneously into work-engaging positions in curvilinear paths in the direction of the advancing work.

28. In a machine of the character described, the combination, with means for continuously advancing the work in a rectilinear path, of oppositely located tool carriers, a plurality of first-action tools and a plurality of second-action tools on each carrier, and means for actuating said carriers to bring said tools simultaneously into work-engaging positions in curvilinear paths in the direction of the advancing work and without interruption of advancing movement.

29. In a flanging machine, the combination, with means for supporting a can body, of a pair of counteracting flanging dies, means for moving said dies simultaneously to and from work-engaging positions whereby said body is self-supported against the forces of the flanging operation, the operative end-portion of each of said dies having a pivotal connection with the body portion thereof, and a spring interposed between said end and body positions and tending to press the former toward a relatively slightly tilted position.

30. In a flanging machine, the combination, with means for supporting and continuously advancing a can body, of a pair of counteracting flanging dies, and means for moving said dies with the work and simultaneously to and from work-engaging positions whereby said body is self-supported in transit against the forces of the flanging operation, and means associated with and forming part of the operative end-portion of each of said dies to facilitate withdrawal of said dies after the flanging operation, substantially as described.

31. In a flanging machine, the combination, with means for supporting and continuously advancing a can body, of a pair of counteracting flanging dies, and means for moving said dies with the work and simultaneously to and from work-engaging positions whereby said body is self-supported in transit against the forces of the flanging operation, the operative end-portion of each of said dies having pivotal connection with the body portion thereof, and a spring interposed between said end and body portions and tending to press the former toward a relatively slightly tilted position.

In testimony of the foregoing, I have hereunto set my hand in the presence of two witnesses.

JULIUS BRENZINGER.
